CALENDER DEVICE

Daniel B. Granzow, Jr., Dayton, Ohio, assignor to The National Cash Register Company, Dayton, Ohio, a corporation of Maryland

Application July 29, 1957, Serial No. 674,879

2 Claims. (Cl. 73—159)

The invention relates to a manually operable calender device.

The principal object of the invention is to provide a device for testing pressure-sensitive material.

Another object of the invention is to test pressure-sensitive coating on record material.

With these and incidental objects in view, the invention includes certain novel features of construction and combinations of parts, a preferred form or embodiment of which is hereinafter described with reference to the drawings which accompany and form a part of this specification.

Of the drawings:

Fig. 1 is an edge view of the calender device.

Fig. 2 is a face view of the calender device.

Fig. 3 is a detail view of the calender device showing the position of the pressure rollers just before they exert pressure on the material to be tested.

General description

For best results, paper such as that produced by the process shown in U. S. patent to Green et al., No. 2,730,457 must attain a high degree of accuracy in dispersion of capsules on its surface. As fully described in said patent, the coated record material comprises oily liquid reactant substance encased in central nuclei in pressure-rupturable microscopic capsules of hardened film-forming hydrophilic colloid materials. Pressure impact of a marking instrument on the surface of this novel record material locally releases the oily nuclei from the capsules and forces the oily liquid into contact with solid reactant attapulgite particles.

The coated paper to be successful in use must attain a high degree of accuracy in the construction of the capsules and their dispersion on the surface of paper.

The device illustrated herein comprises a means of testing such coatings before placing them in use.

Detail description

The device includes two calender rollers 10 and 11, between which paper to be tested is placed. The roller 10 is rotatably mounted in a bracket 12, bifurcated to fit in a recess 13, and pivoted on a stud 14, carried in the recess 13. The amount of movement of the roller 10

2

about the pivot stud 14 is determined by the walls of the recess 13, against which the bracket may rest, as illustrated in Fig. 3. The recess 13 is formed in a handle 15, pivoted to a second handle 16 by stud 17. The handle 16 has rigidly connected thereto a bracket 18, supporting the roller 11. Studs 19 and 20 maintain the bracket rigid on the handle 16.

To use the device, paper 21 is placed between the rollers 10 and 11, and the handles 15 and 16 are grasped to close the rollers tightly against the paper. To insure perfect alinement of the rollers 10 and 11 against each other so as to grip the paper uniformly throughout the length of the rollers, the roller 10 is pivoted, and in the beginning of the closing operation, the roller 10 engages the roller 11 in the manner illustrated in Fig. 3. Further closing of the handles brings the rollers 10 and 11 together in the manner illustrated in Fig. 2. After the paper is firmly gripped between the rollers 10 and 11, the paper is pulled through the device, whereupon the rollers rotate and apply pressure to the paper. The pressure is sufficient to crush the capsules on the surface of the paper, and an impression is made. From the impression made, the operator can determine the quality of the coating on the paper.

The invention is illustrated as a portable device. If desirable, one handle, 15 or 16, can be so constructed that it can be affixed to a bench, table, stand or similar furniture.

While the form of mechanism shown and described is admirably adapted to fulfill the objects primarily stated, it is to be understood that it is not intended to confine the invention to the one form or embodiment herein disclosed, for it is susceptible of embodiment in various other forms.

What is claimed is:

1. An article of manufacture, comprising a pair of arms pivoted together at one end, a bracket fixed to one arm, a second bracket pivotally mounted on the other arm, and a roller carried in each bracket, said rollers movable into engagement with each other, when the handles are moved toward each other, the engagement of the rollers being such as to grip material therebetween throughout the entire length of the rollers.

2. In an article of manufacture comprising a means to apply pressure to material, the combination of a plier-like device having two arms pivoted together, and a roller mounted on each arm within the arms, one roller being mounted to move relative to the arm on which it is pivoted to assure accurate contact between the rollers so as to apply the pressure to the material evenly throughout the lengths of the rollers.
